[57] CLAIM

The ornamental design for a sports bag, as shown and described.

DESCRIPTION

FIG. 1 is a front elevational view of a sports bag showing my new design, the rear elevational view being substantially a mirror image thereof;

FIG. 2 is a top plan view thereof;

FIG. 3 is a bottom plan view thereof;

FIG. 4 is a perspective view of the sports bag in an expanded condition and with the top flap open;

FIG. 5 is a right end elevational view of FIG. 1;

FIG. 6 is a perspective view thereof; and

FIG. 7 is a left end elevational view thereof.

FIG. 1

FIG. 2

FIG. 3

FIG. 4

FIG. 5

FIG. 6

FIG. 7
